CLAIM

The ornamental design for a five-slot computer housing, as shown and described.

DESCRIPTION

FIG. 1 is a top front right side perspective view of a five slot computer housing showing our new design with the access door closed;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof; and

FIG. 8 is an enlarged perspective view thereof, with the access door open.

FIG. 1

FIG. 2
